UNITED STATES PATENT OFFICE.

JOSEPH WALTON WILLIAMS, OF BLABON, NORTH DAKOTA.

DUMPING DEVICE.

1,371,963.

Specification of Letters Patent. Patented Mar. 15, 1921.

Application filed January 30, 1920. Serial No. 355,096.

To all whom it may concern:

Be it known that I, JOSEPH WALTON WILLIAMS, a citizen of the United States, residing at Blabon, in the county of Steele and State of North Dakota, have invented new and useful Improvements in Dumping Devices, of which the following is a specification.

This invention relates to dumping devices and has for its object the provision of a platform interposed within a drive-way and having its floor so mounted that it may tip up to cause dumping of a wagon, sleigh, or motor truck driven thereonto.

An important object is the provision of a device of this character in which the floor is formed of two independently movable sections, one of which is adapted for use for dumping wagons and sleighs and the other of which is adapted for use in dumping motor trucks, means being provided whereby either or both sections may be locked against movement as when the vehicle is moved thereover and gotten into position ready for dumping.

Another object is the provision of a device of this character which is provided with means whereby either or both of the floor sections may be returned to normal position in an easy and efficient manner.

An additional object is the provision of a device of this character which will be comparatively simple and inexpensive in manufacture, highly efficient in use, durable in service, and a general improvement in the art.

With the above and other objects and advantages in view, the invention consists in the details of construction to be hereinafter more fully described and claimed, and illustrated in the accompanying drawings in which—

Figure 1 is a plan view of my device interposed in a drive-way,

Fig. 2 is a side elevation,

Fig. 3 is an end elevation,

Fig. 4 is a cross sectional view on the line 4—4 of Fig. 1,

Fig. 5 is a cross sectional view on the line 5—5 of Fig. 1,

Fig. 6 is an end elevation of the opposite end, showing the platform in elevated position,

Fig. 7 is a longitudinal sectional view showing the inner floor section in dumping position and the outer section held station-

ary, the vehicle being indicated in dotted lines, and

Fig. 8 is a similar view showing both floor sections in dumping position, the vehicle being indicated in dotted lines.

Referring more particularly to the drawings, the numeral 10 designates broadly an elongated rectangular frame which includes sides 11, ends 12, and supporting legs 13 at the ends, and other legs 14 intermediate the ends. This frame is interposed in a suitable drive-way designated by the letter A and this drive-way is provided adjacent the frame 10 with a trap-door B.

Disposed and secured within the frame 10 in spaced relation to the sides 11, are bars 15 which are braced by means of a transverse bar 16 secured upon the underside of the sides 11. These bars 15 extend along the frame as far as the intermediate legs 14. Secured within the other end portion of the frame 10 is a rectangular frame 17 provided with a trap-door 18.

Disposed between the sides 11 of the outer frame 10 and the bars 15 are platform sections 19 which extend the full length of the frame 10 and which are somewhat L-shaped, as shown at 19, so as to fill the spaces between the sides 11 and the rectangular frame 17. These sections 19 are pivotally mounted by short shafts 21 which extend through the sides 11, through the members 19, and through the bars 15.

In order that the sections 19 may be held in normally horizontal position, I provide a shaft 22 journaled between the legs 13 at the end of the platform provided with the trap-doors and this shaft 22 carries arms 23 which are engageable beneath the ends of the sections 19. At one end the shaft 22 carries a lever 24 whereby it may be rocked and this lever is adapted to move between stop pins 25 and 26 on the adjacent leg 13. At their other ends the sections 19 have their upper portions cut away, as shown at 27, for a purpose to be described. The numeral 28 designates the inner platform section which fills the space between the bars 15 and between the frame 17 and the opposite end of the frame 10. This movable section 18 includes longitudinal bars 29 connected by cross bars 30 and 31 upon which are secured suitable boards or planks. The transverse bar 30 is of the same width as the section 28 while the transverse bar 31 projects beyond the sides of the section 28 and

engages within the cut away portions 27 in the sections 19. The member 28 is provided intermediate its ends with a shaft 32 journaled within holes 33 in the sections 19 and 5 resting within recesses 34 in the bars 15. The member 28 is thus pivotally mounted with respect to the frame 10. Secured upon the underside of the transverse bar 30 are cleats 35 which extend beyond the end of 10 the section 28 and which engage beneath the L-shaped portions 20 of the sections 19 adjacent the frame 17 for preventing this end of the section 28 from swinging upwardly beyond the plane of the remainder of 15 the platform.

In order that the section 28 may be held in normally horizontal position, I provide a shaft 36 which is journaled between the legs 14 and which carries arms 37 adapted to 20 engage beneath the ends of the bars 29. This shaft 36 carries at one end a lever 38 movable between stops 39 and 40 whereby the arms 37 may be moved into and out of engagement with the bars 29.

25 In order that the platform sections 19 and also the section 28 may be returned to normal position after being moved to dumping position, as will be hereinafter described, I provide a shaft 41 journaled between the legs 13 at the other end of the frame 10. Connected with this shaft are chains 42 which are connected with the adjacent ends of the bars 29. This shaft 41 serves the purpose of the windlass and is 30 provided at one end with a sprocket 43 about which is trained a sprocket chain 44 which is in turn trained about another sprocket 45 mounted upon the stub-shaft 46 carrying a gear 47 with which meshes 35 a second gear 48 having its shaft 49 squared for engagement therefrom of a handle 20.

The operation of the device is as follows:

Under normal conditions the platform sections 19 and 28 are all horizontally disposed and lie flush with the top of the frame 10. At such time the levers 24 and 38 are in position engaging the stops 25 and 39 and the arms 23 and 37 engage beneath the end portions of the sections 19 and 50 bars 29, respectively. It will be observed that movement of any of the platform sections will then be impossible.

When it is desired to dump a motor truck, the truck is driven onto the drive-way A 55 and onto the platform within the confines of the frame 10. The wheels of the truck will rest entirely upon the platform sections 19 and the rear end of the truck will be adjacent the trap-door B. The lever 24 is 60 then moved into engagement with the stop 26 and this movement will result in disengagement of the arms 23 with the ends of the sections 19. The lever 38 is moved into engagement with the stops 40 so as to move 65 the arms 37 out of engagement with the ends

of the members 29. The sections 19 and 28 may then be moved together. The weight of the truck will then cause the sections 19 and 28 to swing upon the shafts 21 and the rear end of the truck will then be inclined 70 downwardly, as shown in Fig. 8. It will be obvious that when the tail-gate of the truck is raised the contents will pass through the trap-door B. When the truck is then dumped, the operator turns the handle 50 75 and thereby rotates the shaft 41 which will result in winding thereonto the chains 42, causing the inner section 28 to be pulled downwardly, whereupon the engagement of the projecting ends of the cross bars 31 80 within the cut-away portions 27 of the sections 19 will cause the sections 19 also to be returned to normal position. The truck may then be driven off from the platform.

When it is desired to dump a wagon or 85 sleigh, the levers 24 and 38 are moved into engagement with the stops 25 and 40, respectively, so as to lock all the platform sections against movement. The wagon or sleigh is then driven onto the drive-way A and onto 90 the platform of my device, the wheels or runners, as the case may be, resting entirely upon the section 28. The operator then moves the lever 38 into engagement with the stop 39 to disengage the arms 37 from the 95 bars 29, whereupon the weight of the load will cause the section 28 to swing downwardly into inclined position, as shown in Fig. 7. When the tail-gate of the wagon or sleigh is then raised it will be obvious that 100 the load will be discharged through the trap-door 18 within the frame 17. The shaft 41 is then rotated as in the previously described operation to return the section 28 to normal horizontal position, after which 105 the vehicle is driven off.

From the foregoing description and a study of the drawings it will be apparent that I have thus provided a simply constructed and easily operated device for 110 dumping vehicles of various types in a thorough and efficient manner. It will also be observed that if it is desired to associate with my device some scale for weighing loads thereon, the draft animals in the case 115 of a wagon or sleigh may be driven entirely across my device and allowed to stand upon the drive-way at one end thereof while the load is being weighed and dumped.

While I have shown and described the 120 preferred embodiment of my invention, it is of course to be understood that I reserve the right to make such changes in the form, construction, and arrangement of parts as will not depart from the spirit of the invention 125 or the scope of the subjoined claims.

Having thus described my invention, I claim:

1. A device of the character described comprising an elongated rectangular frame 130

- interposed in a drive-way, a pair of bars secured within said frame in spaced parallel relation to the sides thereof and terminating short of the length of the frame, said bars being provided intermediate their ends with recesses opening out to their upper edges, platform sections disposed between the sides of said frame and said bars, and pivotally connected intermediate their ends therewith, means for holding said sections in normally horizontal position, an inner section disposed between said bars and having a shaft disposed within said recesses and journaled through said first named sections, means for normally holding said last named section in horizontal position, said first and second named sections being tilttable when both of said holding means are released, and said second named section being independently tilttable when said second named holding means is released, and means for returning said sections to normal position.
2. A device of the character described comprising an elongated rectangular frame interposed in a drive-way, a pair of bars secured within said frame in spaced parallel relation to the sides thereof and terminating short of the length of the frame, said bars being provided intermediate their ends with recesses opening out to their upper edges, platform sections disposed between the sides of said frame and said bars, and pivotally connected intermediate their ends therewith, means for holding said sections in normally horizontal position, an inner section disposed between said bars and having a shaft disposed within said recesses and journaled through said first named sections, means for normally holding said last named section in horizontal position, said first and second sections being tilttable when both of said holding means are released, and said second named section being independently tilttable when said second named holding means is released, and means for returning said sections to normal position, said last named means comprising lateral extensions on said last named section engaging the top edges of said first named section, and a windlass structure connected with said second named section. 30 35 40 45 50

In testimony whereof I affix my signature.

JOSEPH WALTON WILLIAMS.
